Primary Examiner — Jennifer Rivard*Assistant Examiner* — Jenny lou M Binas(74) *Attorney, Agent, or Firm* — McDermott Will & Emery LLP(57) **CLAIM**

The ornamental design for a vacuum water basin, as shown and described.

DESCRIPTION

FIG. 1 is a top perspective view of a vacuum water basin showing the new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The shading presented in the accompanying drawings is provided merely to highlight the contour of the invention and is not intended to be illustrative of texture or gloss.

The broken lines show portions of the vacuum water basin that form no part of the claimed design.

1 Claim, 7 Drawing Sheets(56)
